US0D1004335S

(12) **United States Design Patent** (10) **Patent No.:** **US D1,004,335 S**
(45) **Date of Patent:** **** Nov. 14, 2023**

(54) **CARPET**

(71) Applicant: **Yiwu Ligao Technology Co., Ltd,**
YiWu (CN)

(72) Inventor: **Linfei Chen**, Yiwu (CN)

(73) Assignee: **Yiwu Ligao Technology Co., Ltd.,**
Yiwu (CN)

(**) Term: **15 Years**

(21) Appl. No.: **29/844,993**

(22) Filed: **Jul. 3, 2022**

(51) LOC (14) Cl. **06-11**

(52) U.S. Cl.

USPC **D6/583**; D6/589

(58) **Field of Classification Search**

USPC D5/56, 57, 63; D6/582-583, 587-588,

D6/592; D12/203; D21/792

CPC A47G 27/0206; A47G 27/0225; A47G

27/0237; A63B 6/00; A47L 23/266
